Primary Examiner — Terry Wallace*(74) Attorney, Agent, or Firm* — Stuart M. Goldstein(57) **CLAIM**

The ornamental design for a beverage cooler, as shown and described.

DESCRIPTION

FIG. 1 is a perspective view from the top, front, right corner of a beverage cooler;

FIG. 2 is a left side elevation view of the beverage cooler of FIG. 1;

FIG. 3 is a right side elevation view of the beverage cooler of FIG. 1;

FIG. 4 is a front elevation view of the beverage cooler of FIG. 1, the rear elevation view being a mirror image thereof;

FIG. 5 is a top plan view of the beverage cooler of FIG. 1;

FIG. 6 is a perspective view from the top, front, right corner of a partially-assembled beverage cooler that is shown without the beverage retaining strap of FIG. 1;

FIG. 7 is a left side elevation view of the partially-assembled beverage cooler of FIG. 6;

FIG. 8 is a right side elevation view of the partially-assembled beverage cooler of FIG. 6;

FIG. 9 is a front elevation view of the partially-assembled beverage cooler of FIG. 6, the rear elevation view being a mirror image thereof; and,

FIG. 10 is a top plan view of the partially-assembled beverage cooler of FIG. 6.

The broken lines are for illustration purposes only and form no part of the claimed design.
